[57] CLAIM

The ornamental design for spray hood for use with a life jacket, as shown and described.

DESCRIPTION

FIG. 1 is a front and side perspective view of a spray hood for use with a life jacket showing our new design;

FIG. 2 is a left side view thereof; the right side view is a mirror image of FIG. 2;

FIG. 3 is a rear view thereof;

FIG. 4 is a perspective view showing the sprayhood being worn and located on an inflated lifejacket, the wearer's head and the lifejacket being shown in chain-dotted outline;

FIG. 5 is a front view showing the sprayhood being worn and located on an inflated lifejacket, the wearer's head and the lifejacket being shown in chain-dotted outline;

FIG. 6 is a bottom plan view thereof; and,

FIG. 7 is a top plan view thereof.

The wearer's head and life jacket shown in dotted lines are for illustrative purposes only and form no part of the claimed design.
